UNITED STATES PATENT OFFICE.

BARTHELEMY MAYOUX AND CHARLES VERCHÈRE, OF IZIEUX, FRANCE, ASSIGNEES
TO CÉSAR CORRON, OF ST. CHAMOND, FRANCE.

APPARATUS FOR CHARGING DYE-VATS.

960,662.

Specification of Letters Patent.

Patented June 7, 1910.

Application filed June 21, 1907. Serial No. 380,072.

To all whom it may concern:

Be it known that we, BARTHELEMY MAYOUX and CHARLES VERCHÈRE, citizens of the French Republic, and residing at Izieux, 5 Department Loire, in France, have invented certain new and useful Improvements in Apparatus for Charging Dye-Vats, of which the following is a specification.

This invention relates to improvement in 10 apparatus for charging dye-vats.

The operations of dyeing and of preparing goods for the reception of dye involve the use of a series of baths, and for this purpose it has hitherto been usual to transfer the goods from one vat to another, either 15 by hand or by mechanical means.

The purpose of the present invention is to allow of effecting the successive operations of preparing and dyeing with apparatus of great simplicity, occupying a very 20 small amount of space, without changing the position of the goods or apparatus. For this purpose the baths are successively introduced from and returned to reservoirs 25 adjacent the vats by pneumatic means.

A construction embodying the invention is illustrated in the annexed drawing, in which—

Figure 1 is an elevation of the apparatus, 30 arranged for working with compressed air. Fig. 2 is a plan view thereof, and Fig. 3 a cross-section on the line 3—3 of Fig. 1, on a larger scale.

Referring to Figs. 1-3, the double frame 35 A, with skein-holders *a*, is supported by a hydraulic elevator B by means of which it can be raised to lift the skeins from the baths. At each side of the frame, below the skein-holders *a*, two vats C C₁ are permanently fixed, and all the successive operations of dyeing are performed in these two 40 vats. Below the vats C C₁, or in any other convenient position, there are reservoirs D D₁ into which the baths are discharged after 45 use, in order to be preserved for further use. The transfer of the liquid takes place by means of compressed air, and may be effected in the following manner.

First method.—Air for raising the baths 50 is compressed in a drum E by means of a compressor F connected to the drum by a pipe *f*, and passes from the said drum into a pipe G. The latter is connected to all the reservoirs by pipe H provided with branches 55 H₁ each having a three-way cock I I₁, which

enable the drum E to be placed in communication with the respective reservoirs, or the interiors of the reservoirs to be placed in communication with the outer atmosphere while the baths are being heated by steam 60 from a pipe J.

Below the two vats C C₁ there is a pipe K, which can be placed in communication with the one or other vat by means of valve L or L₁ respectively and with the reservoir D or D₁ by means of valves M or M₁ provided with tubular prolongations *m* *m*₁ extending to within a short distance of the bottoms of the reservoirs D D₁ respectively. Two valves N N₁ allow of emptying the vats 70 without refilling the reservoirs D D₁, the liquid being discharged into a waste-pipe O or O₁. When for example the valve M is opened and compressed air is admitted to the reservoir D liquid from the latter as- 75 cends through the tube *m* to the pipe K, lifts the valves L and L₁ and passes into the vats C and C₁. The valve M is then closed and the cock I opened to place the interior of the reservoir in communication with the 80 atmosphere.

For emptying the vats C C₁ the valves L and L₁ are lifted and the valve M opened, whereupon the liquid flows back to the reservoir D, or one of the valves N N₁ is opened 85 and the liquid passes away through the pipe O or O₁.

If the contents of the reservoir D₁ is to be used the cock I₁ and valve M₁ are opened.

The valves M M₁ are controlled by levers 90 P one of which is shown in Fig. 1, the other being on the other side of the apparatus. The valves N N₁ are controlled by levers Q of which one is shown in Fig. 1. The levers P and Q may be operated in any convenient 95 way, for example directly by hand, as in the case of the lever P, or by means of a chain-wheel, as in the case of the lever Q.

The frame with the skein-holders is lifted by means of the hydraulic elevator B, on 100 the piston of which the frame rests. Water under pressure is supplied to the elevator by a pipe b, which can be connected by a three-way cock R to a supply-pipe S. The frame descends by gravity when the pipe b 105 is placed in communication with the discharge-pipe T by means of the cock R.

Second method.—The air may be compressed by hydraulic power if a sufficient head of water is available. In this case 110

- water from an elevated source of supply is conducted to a reservoir U placed at a level somewhat higher than that of the vats C C₁. When the baths are to be raised from the reservoirs D D₁ to the vats C C₁ the cock V admitting water to the reservoir U is opened, and the water flows into the reservoir U through the pipe V₁. The air-cock I is opened to place the reservoirs U and D 10 in communication with each other, so that the bath is raised by the air expelled from the reservoir U, the supply of liquid to the vat being proportional to the amount of water admitted to the reservoir U. When 15 the vat is full the cock V is closed. The water is discharged from the reservoir U and used for washing purposes, the reservoir being refilled with air admitted by a valve W. The discharge-pipe U₁ leading from the 20 reservoir U is connected by a pipe u₁ and valve u to the vats. The arrangement of the reservoirs D is the same as described with reference to the first method of operation.
- What we claim as our invention and desire to secure by Letters Patent of the United States is:—
1. In apparatus for the purpose set forth the combination of a dye vat, a plurality of closed dye bath reservoirs, separate means 30 of communication between each reservoir and the bottom of the dye vat, valves in said communications for selectively opening and closing the same, means for varying the air pressure prevailing in the respective 35 reservoirs to cause liquid to pass from the same into the dye vat or from the latter to the respective reservoirs and means for supplying water to the dye vat independently of said reservoirs.
  2. In apparatus for the purpose set forth the combination of an open dye vat, means for suspending goods to be dyed therein, said suspending means being capable of vertical movement, a plurality of closed dye bath 40 reservoirs, separate means of communication between each reservoir and the bottom of the dye vat, valves in said communications for selectively opening and closing the same, means for varying the air pressure prevailing in the respective 45 reservoirs to cause liquid to pass from the same into the dye vat or from the latter to the respective reservoirs.
  3. In apparatus for the purpose set forth the combination of a dye vat, a plurality of closed dye bath reservoirs, separate means of communication between each reservoir and the bottom of the dye vat, valves in said communications for selectively opening and closing the same, means for varying the air pressure prevailing in the respective 50 reservoirs to cause liquid to pass from the same into the dye vat or from the latter to the respective reservoirs and means for supplying water to the dye vat independently of said reservoirs.
  4. In apparatus for the purpose set forth the combination of a dye vat, a plurality of closed dye bath reservoirs beneath the level of the bottom of said vat, separate means of communication between each reservoir and the bottom of the vat, valves in said communications, a closed air reservoir above the said dye bath reservoirs, valved communications between the upper part of the air reservoir and the dye bath reservoirs, 60 and means for admitting water under pressure to the dye vat.
  5. In apparatus for the purpose set forth the combination of a dye vat, a plurality of closed dye bath reservoirs beneath the level of the bottom of said vat, separate means of communication between each reservoir and the bottom of the vat, valves in said communications, a closed air reservoir above the said dye bath reservoirs, valved communications between the upper part of the air reservoir and the dye bath reservoirs, means for admitting water under pressure into said air reservoir, and valved communication between the lower part of the air reservoir and the dye vat.
- In witness whereof we have signed this specification in the presence of two witnesses.
